UNITED STATES PATENT OFFICE.

HENRY UNTERMAYER, OF NEW YORK, N. Y.

DESIGN FOR A WATCH-CASE.

SPECIFICATION forming part of Design No. 12,238, dated April 26, 1881.

Application filed March 5, 1881. Term of patent 7 years.

To all whom it may concern:

Be it known that I, HENRY UNTERMAYER, of the city, county, and State of New York, have invented a new and Improved Design for Watch-Cases, of which the following is a full, clear, and exact description.

In the drawing my newly-designed watch-case is shown by a side elevation.

Watch-cases have heretofore been made to represent shells.

My invention relates to the configuration of such shell watch-cases at the bottom portion, where the two parts of the case are hinged together. The case is formed at the bottom with a rib projecting beyond the outline of the shell, so as to give a straight bottom line to the case.

A is the case, made in shell form, with scal-

loped edges, and formed at the base or bottom with a projecting rib, *a*, having beveled ends *b*. The rib *a* is formed by a projection on each half of the case, and the surface may be ornamented in any desired manner.

Having thus described my invention, I claim as new and desire to secure by Letters Patent—

The design for watch-cases, which consists in a scalloped shell having the straight rib or projection *a* at the base, as shown and described.

HENRY UNTERMAYER.
